UNITED STATES PATENT OFFICE

GILBERT ALAN ROBINSON, OF SUTTON-ON-HULL, ENGLAND

METHOD OF MAKING METAL CONTAINERS

Application filed March 31, 1932. Serial No. 602,379, and in Great Britain January 5, 1931.

This invention relates to rectangular pyramid-topped or rectangular flat-topped cans, canisters and like metal containers of the type wherein the upper part or top of the body affords a reduced outlet or neck.

It has previously been proposed to produce the domed upper portion or neck and the base of a sheet metal bottle or receptacle by forming overlapping corrugations at the end 10 of a tubular body, and also to produce bodies of sheet-metal barrels or like vessels by a stamping or pressing operation resulting in the formation of outwardly projecting wings which are subsequently flattened against and 15 welded or otherwise secured to the exterior surface of the vessel.

According to the invention, the pyramidal or flat top and the wall of the body are made integral by forming from one or more 20 blanks each constituting a portion of the wall and the top, a tubular body which is brought to the desired shape by a series of longitudinal pleats or folds being made therein at one end to secure the desired pyramid or flat 25 form, and said pleats or folds are pressed into contact with the inner or outer face of the pyramidal or flat top portion so formed.

In an embodiment of the invention, a sheet 30 metal blank is formed into a tube of the required rectangular cross section for the body of the can, canister or the like and the adjacent edges seamed or otherwise secured together, whereupon that end of the tubular blank which is to constitute the pyramidal or flat upper part or top of the can body is 35 tapered or flattened by forming therein a series of longitudinal pleats or folds appropriately spaced apart and each increasing in width toward that edge which is to constitute the outlet, the folds or pleats being flattened against the inner or outer face of the pyramidal or flat top portion so formed. The reduced outlet may be fitted with the 40 usual pouring spout or neck rim, and a handle may be secured to the tapered or flattened upper part of the can body, whilst a bottom 45 would be secured on the opposite end of the body in the usual manner.

In order that the invention may be clearly 50 understood and readily carried into effect,

the same will now be more fully described with reference to and by the aid of the embodiments illustrated by way of example in the accompanying drawing; wherein:—

Figure 1 is a perspective view of the upper portion of a rectangular pyramid-topped can.

Figure 2 is a sectional plan view of a square pyramid-topped can, the section being taken transversely through the pyramid top.

Figure 3 is a perspective view of the upper portion of a square flat-topped tin, the top being afforded by folding or pleating the blank.

Referring to Figure 1 of the drawing, the rectangular can 1 is made by forming a tube of rectangular cross section from a blank, and then forming the upper pyramid part 2 by folding inwardly one end of the rectangular tube at its corners so as to afford four double and inwardly directed triangular flaps or wings 3. This has the effect of drawing in the intermediate taper portions at the end of the rectangular tube to attain the desired pyramid shape, whereupon the flaps or wings 3 are flattened against the inner faces of the pyramid top, as shown, and may be secured thereto by soldering or welding (see Figure 2). A pouring spout or neck 4 is then secured in position and a bottom (not shown) is secured to the opposite end of the body to complete the can.

Referring to Figure 3 of the drawing the flat top 7 is made by folding or pleating the end of a tubular body part of square section formed from a blank inwardly at the corners to afford inwardly directed flaps 3 which are then pressed into contact with the inner face or underside of the intermediate portions and soldered in position. A square pouring spout or neck 4 is then applied around the restricted outlet afforded at the centre of the top.

Instead of single pleats or folds as above described, multiple pleats or folds may be formed to obtain the desired flat or pyramid top. Thus each pleat or fold at the corners may be adapted to afford two flaps which may be pressed into contact with the adja-

cent inner or outer faces of the top and soldered thereto one at each side of the pleat or fold.

Although described as made from a single blank it is obvious that two or more blanks may be employed, each blank constituting a portion of the wall and the top.

Any corners or edges of the container may be grooved or corrugated to afford additional strength or rigidity.

I claim:—

1. The method of making a metal container from a blank which consists in forming a hollow body from the blank, folding the upper portion of the body at spaced points inwardly to provide an inclined top and four inwardly extending triangular flaps, flattening the flaps against the inner face of the top, securing the flaps to the top and inserting a spout at the reduced end opening in the mouth of the top.

2. The method of making a metal container from a blank which consists in forming a quadrilateral body from the blank, folding the upper portion of the body at its corners inwardly to provide a pyramidal top and four double and inwardly extending triangular flaps, flattening the flaps against the inner faces of the pyramidal top, and inserting a spout in the reduced end opening formed at the mouth of the top.
